UNITED STATES PATENT OFFICE.

HERMAN ROESE, JR., OF SYRACUSE, NEW YORK.

SHOE.

1,117,246.

Specification of Letters Patent.

Patented Nov. 17, 1914.

Application filed February 12, 1912. Serial No. 676,945.

To all whom it may concern:

Be it known that I, HERMAN ROESE, Jr., of Syracuse, in the county of Onondaga, in the State of New York, have invented new and useful Improvements in Shoes, of which the following, taken in connection with the accompanying drawings, is a full, clear, and exact description.

This invention relates to shoes and pertains more particularly to the detail construction thereof by means of which a distinct, natural and hygienic shape is given thereto.

Heretofore in the manufacture of shoes it has been customary to construct the same with an upward curve at the instep and level up the shoe by placing a heel of greater or less height at the rear portion of the sole, thus throwing substantially the whole weight of the body upon the ball of the foot; extending the muscles along the front of the leg and contracting those at the rear. It has also been customary to narrow the sole by substantial inward curves at the point where the shoe rises at the instep and thus the foot is tightly confined and forced to conform to the upward bend of the sole at that point. This feature further tends to throw the weight of the body upon the ball of the foot and causes an unnatural development of the cords and muscles by stretching the front muscles of the foot and leg and contracting those in the rear, and placing the whole strain of walking upon the front muscles.

My object therefore is to overcome these difficulties and disadvantages by constructing a shoe with a perfectly flat sole, and without a heel or the necessity of any, and by making the sole with only a slight contraction at the instep the foot is allowed to assume its natural shape and as nearly as possible is in the same position as when bare. The muscles of the foot thus assume their natural position in which they are

able to sustain a greater weight and a greater strain and may be subjected to the same for a greater length of time with less weariness.

Having the above objects and uses in mind, my invention therefore consists in the new and novel features of construction hereinafter described, in connection with the accompanying drawings which form a part thereof.

Figure 1 is a view of a shoe. Fig. 2 is a bottom view of the same. Fig. 3 is a side view of the same.

The shoe comprises the sole —1— perfectly flat, as best shown in Fig. 3, and having one side provided with a very slight inward curve —2— at the instep, substantially parallel with the long and gradual curve of the side —3—. The top —4—, of substantially the usual shape, is sewed to the sole 60 or attached in any suitable manner. It is apparent that the sole determines the shape of the lower portion of the shoe and that by this construction the bottom of the shoe is flat and the instep very broad—for the purposes above mentioned.

What I claim is:

The herein described shoe comprising an upper composed of an ankle and foot portion, and a flat sole of substantially equal 75 thickness from fore to aft, and having a slight inward recess upon the inner side at the instep portion, the foot portion of the upper upon the inner side of the shoe lying in substantially a straight line from the heel 80 to the toe, the outer side of the foot portion of the upper disposed in a long gradual curve from heel to toe.

In witness whereof I have hereunto set my hand on this 6 day of February 1912.

HERMAN ROESE, JR.
